CLAIM

The ornamental design for a trampoline, as shown and described.

DESCRIPTION

FIG. 1 is a perspective view of a trampoline;
FIG. 2 is a front elevational view of the trampoline of FIG. 1;
FIG. 3 is a right side elevational view of the trampoline of FIG. 1;
FIG. 4 is a left side elevational view of the trampoline of FIG. 1;
FIG. 5 is a rear elevational view of the trampoline of FIG. 1;
FIG. 6 is a bottom view of the trampoline of FIG. 1; and,
FIG. 7 is a top view of the trampoline of FIG. 1.

(Continued)

The broken line showing of portions of the trampoline depicts environment and forms no part of the claim.

1 Claim, 7 Drawing Sheets
